*Inventor.**Charles Griffith*

United States Patent Office.

CHARLES GRIFFITH, OF NEW YORK, N. Y.

Design No. 2,815, dated October 22, 1867.

DESIGN FOR A TRADE-MARK.

The Schedule referred to in these Letters Patent and making part of the same.

TO ALL WHOM IT MAY CONCERN:

Be it known that I, CHARLES GRIFFITH, of the city, county, and State of New York, have invented a new and improved Design for Trade-Mark; and I do hereby declare that the following is a full, clear, and exact description thereof, which will enable others skilled in the art to understand the same, reference being had to the accompanying drawing, forming part of this specification.

The drawing represents a face view of my new trade-mark.

This invention relates to a new design for a trade-mark, which is composed of a star, A, and a two-armed square, B. The star is arranged between the arms of the square, above the same, as shown. Within the square are arranged the three letters, S, I, and N, representing the initials of Sir Isaac Newton. The colors of the various parts may be changed at will. The letters may be of any suitable style or pattern.

I claim as new, and desire to secure by Letters Patent—

The design for a trade-mark, made substantially as herein shown and described.

CHARLES GRIFFITH.
